[57] CLAIM

The ornamental design for a cosmetic case, as shown and described.

DESCRIPTION

FIG. 1 is a top front left perspective view of a cosmetic case showing my new design;

FIG. 2 is a perspective back and bottom view thereof;

FIG. 3 is a top plan view thereof;

FIG. 4 is a front elevational view thereof;

FIG. 5 is a left side elevational view thereof;

FIG. 6 is a bottom plan view thereof;

FIG. 7 is a rear elevational view thereof;

FIG. 8 is a right side elevational view thereof;

FIG. 9 is a top front left perspective view of a cosmetic case showing a modified form of my new design wherein the top is transparent;

FIG. 10 is a top plan view thereof, the other views being identical to those shown in FIGS. 4-8.

FIG. 1FIG. 2

FIG. 3FIG. 4*FIG. 5

FIG. 6

FIG. 7

FIG. 8

FIG. 9FIG. 10
